UNITED STATES PATENT OFFICE

PAUL E. PAPKE, OF CHICAGO, ILLINOIS

DESIGN FOR AN AIRPLANE

Application filed June 19, 1931. Serial No. 40,276. Term of patent 14 years.

To all whom it may concern:

Be it known that I, PAUL E. PAPKE, a citizen of the United States, and a resident of Chicago, in the county of Cook and State of Illinois, have invented the new, original, and ornamental Design for Airplane, of which the following is a specification, reference being had to the accompanying drawings, forming part thereof.

Figure 1 is a top plan view of an airplane showing my new design,

Figure 2 is a side elevational view thereof, and

Figure 3 is a front elevation of the airplane as viewed in flight.

I claim:

The ornamental design for an airplane, substantially as shown.

Signed at Chicago in the county of Cook and State of Illinois, this 15 day of June, A. D. 1931.

PAUL E. PAPKE.
